Specification for Design.

Patented Nov. 18, 1919.

Application filed August 27, 1919. Serial No. 320,321. Term of patent 14 years.

To all whom it may concern:

Be it known that I, ALFRED C. GILBERT, a citizen of the United States, residing in New Haven, New Haven county, Connecticut, have invented a new, original, and ornamental Design for a Toy Hand-Truck, of which the following is a specification when taken in connection with the accompanying drawing.

In the drawing:

Figure 1 is a perspective view of a toy hand truck embodying my new design.

Fig. 2 is a top plan view of the same; and

Fig. 3 is a front end view of Fig. 2.

What I claim is:

The ornamental design for a toy-hand truck; substantially as shown.

ALFRED C. GILBERT.
